[57] CLAIM

The ornamental design for a combined stand and con-

tainer for storing and dispensing gasoline or the like, as shown and described.

DESCRIPTION

FIG. 1 is an elevational view of a combined stand and container for storing and dispensing gasoline or the like showing my new design;

FIG. 2 is a top plan view;

FIG. 3 is an elevational view looking from the right of FIG. 1;

FIG. 4 is a bottom plan view;

FIG. 5 is a view similar to FIG. 1 but showing a second embodiment of my new design;

FIG. 6 is a top plan view;

FIG. 7 is an elevational view looking from the right of FIG. 5;

FIG. 8 is a bottom plan view;

FIG. 9 is a view similar to FIG. 1 but showing a third embodiment of my new design;

FIG. 10 is a top plan view;

FIG. 11 is an elevational view looking from the right of FIG. 9;

FIG. 12 is a bottom plan view;

FIG. 13 is a view similar to FIG. 1 but showing a fourth embodiment of my new design;

FIG. 14 is a top plan view;

FIG. 15 is an elevational view looking from the right of FIG. 13; and

FIG. 16 is a bottom plan view.

The broken lines in FIGS. 1, 3, 5, 7, 9 and 11 showing a portion of a dispensing tube are for the purpose of illustrating environmental use only.

Fig. 1.Fig. 3.Fig. 2.Fig. 4.Fig. 5.Fig. 7.Fig. 6.Fig. 8.*Fig. 9.**Fig. 11.**Fig. 10.**Fig. 12.*Fig. 13.Fig. 15.Fig. 14.Fig. 16.
